UNITED STATES PATENT OFFICE.

IRVING E. ASKE, OF DULUTH, MINNESOTA.

FUEL HEATER.

Application filed May 12, 1924. Serial No. 712,654.

My invention relates to fuel heaters and has for its object the provision of a cheap and effective fuel heater adapted to be heated by heated fluids or gases, as by the exhaust of a hydrocarbon engine. It has for a further object the provision of a novel fuel heater adapted to volatilize or fume liquid particles of fuel, as for hydrocarbon engines. With these and other objects in view, it consists of the structures, combinations and arrangements of parts hereinafter described and claimed.

In the drawings, the figure shows an elevation, partly broken away, of one form of a mixture-supply manifold, and a fragmentary elevation of one form of an engine exhaust manifold, partly broken away, in cooperative relation to said supply manifold; said manifolds showing my invention embodied there-

20 in.

In the drawings, 1 is a mixture supply conduit or manifold for supplying fuel mixture to a hydrocarbon engine, the intake end of which manifold is indicated at 1^a, at which end it is adapted to be connected in any suitable manner to the throat of a carburetor not shown, but well known to the art. The outlet ports of said mixture manifold are indicated by broken lines at 1^b and 1^c, respectively, at 25 which points said supply manifold is adapted to be connected in any suitable manner or by any suitable means to a hydrocarbon engine not shown. Intermediate of said outlet ports a dome 1^d is formed upon said supply manifold, through which dome a heating rod 2 is directed any suitable distance into a chamber 2^a within said dome or into said manifold. Said rod may, if desired, be tubular, but I prefer to make it solid. It is made 30 of any suitable heat-conducting metal or composition, preferably of copper and preferably of a better heat-conducting material than cast iron or than the material of which said supply or exhaust manifolds are made. Said 35 rod is secured in said dome in any suitable manner or by any suitable means, but I prefer to make it of the same diameter as the aperture for its passage and to force one end of it through said aperture with a suitable press, 40 whereby a tight fit is assured.

Said supply manifold is so positioned with respect to an exhaust manifold 3 as to bring said dome close to one of the walls of said exhaust manifold, and preferably partly enveloped by such wall. Extending through 45 said exhaust manifold is a heater rod 4 of any

suitable construction adapted to contact with the outer end of said rod 2 and to transmit heat to said rod 2. It is desirable that such contact should be a pressure contact to facilitate the transmission of such heat; I therefore prefer to thread the contacting end of said rod 4 and the aperture of the wall of said exhaust manifold through which said contacting end passes, whereby said contacting end 60 is adapted to engage said wall and to be screwed into pressure contacting position with respect to said rod 2. Said rod 4 may be tubular or solid, but I prefer to make it solid, said rod 4 may also be made of any 70 suitable metal or composition or substance, preferably of a better heat-conducting material than the material of said exhaust manifold or than cast iron. If desired, either or both of said rods may be hollow and filled 75 with a different metal or material than the walls of the rod. If desired, a single rod common to both of said manifolds may be used in place of the rods 2 and 4, and may be mounted or secured in said manifolds in any 80 suitable manner or by any suitable means, as in the same manner that said rod 2 is secured in said dome.

It will be understood that said dome, although shown spaced slightly from said exhaust conduit, will be positioned as close to said conduit as may be possible or practicable, and that said invention is not intended to be limited to use with manifolds of the forms shown or limited to use with any "manifold" type of conduits.

In operation, the hot exhaust gases from the engine cylinders in passing through said exhaust manifold, heat said rod 4, which because of its great conductivity and its pressure contact with said rod 2, heats said rod 2 to a high temperature, but not sufficiently hot to explode the fuel mixture in said supply manifold.

The liquid particles of fuel entering said supply manifold are, because of their weight and speed, projected out of the main current of gas and into said dome and against said rod 2 and are thereby heated and converted into hot dense fumes, which being 100 light are drawn back into the current of gases flowing through the branches of the manifold to the engine cylinders. It will be noted that this vaporizer requires no special expenditure of fuel to generate the heat by 105 which it is operated, and that it does not explode or burn or dilute any of the fuel flowing

to the engine cylinders. The fuel mixture is thus left in full strength and efficiency; such efficiency being greatly increased by the pre-heating by my said invention, which is especially desirable when using low grade, or heavy hydrocarbon fuel oils or mixtures. It will be further noted that in one form of my said invention said heating rod is not in the direct draft from the intake of the fuel manifold to its outlets, and the cooling effect of said draft is thus in a material degree evaded.

It is obvious that my said invention may be modified or altered in various particulars within the scope and spirit of my claim.

What I claim is—

The combination of a hydrocarbon fuel supply manifold having an intake port and a dome formed thereon approximately in axial alignment with said intake port, of a heat transmitting rod extending through the wall of said dome into the chamber within said dome, an exhaust manifold for products of combustion, and a heat transmitting rod adapted to contact with the first said rod and extending through the wall of said exhaust manifold into the passage for the products of combustion therein.

In testimony whereof, I hereunto affix my signature. 30

IRVING E. ASKE.
